UNITED STATES PATENT OFFICE.

CHARLES J. AHRENFELDT, OF NEW YORK, N. Y.

DESIGN FOR A PLATE.

SPECIFICATION forming part of Design No. 24,958, dated December 10, 1895.

Application filed November 17, 1894. Serial No. 529,190. Term of patent 7 years.

To all whom it may concern:

Be it known that I, CHARLES J. AHRENFELDT, a citizen of the United States, residing in the city of New York, county and State of New York, have invented and produced a new and original Design for a Plate, of which the following is a specification.

The accompanying drawings represent a plate embodying my design, and consist of Figure 1, which is a plan view of said plate with the ornamentation displayed upon it in relief, and Fig. 2, which is a cross-section of the same.

The essential features of my design consist of a plate provided with a combination of arabesque and escaloped ornamentation, as shown in the accompanying drawings.

In Fig. 1, A A A are the arabesque ornamentations; B B B are the escaloped ornamentations; C is the edge of the plate, and D is the interior surface of the same. The escaloped ornamentations B B B are located near the edge of the plate and commence in an

abrupt wave-like double edge near the edge of the plate and extend toward the center, gradually merging in the smooth interior surface. The edges of these ornamentations are approximately parallel to the edge of the plate, and the ornamentations are alternated with the three arabesque ornamentations around the periphery of the plate. These latter ornamentations A A A are scroll-like in form, consisting of a series of curved lines with peristaltic terminations. They have a slight escalop on one side near the edge of the plate. The edge of the plate C is segmented by indentations arranged so as to present larger and smaller segments alternately. The interior surface D is smooth.

What I claim is—

The design for a plate substantially as herein shown and described.

CHARLES J. AHRENFELDT.
